INSULATING END POST.

1,376,647.

Specification of Letters Patent.

Patented May 3, 1921.

Application filed December 20, 1919. Serial No. 346,223.

To all whom it may concern:

Be it known that we, EDWARDS F. SCHERMERHORN and WILLIAM PATON THOMSON, citizens of the United States, residing, respectively, at Brooklyn and New York, in the county of Kings and New York and State of New York and New York, have invented certain new and useful Improvements in Insulating End Posts, of which the following is a specification.

This invention relates to the subject of insulation for rail joints and more particularly to a novel construction of insulator for rail joints employed as the end post insulation between the abutting ends of the rails.

Insulators of the end post type are quite frequently exposed and subject to the destructive forces of the pounding car wheels passing over the joint. This primarily is due to the fact that ordinarily the insulating end post for insulated rail joints is of the cross-sectional area and contour of the adjoining rail ends with its head member of normal width and height and lying flush or nearly flush with the running surface of the rails so that in case of wearing of the rails or joint parts the head of the end post becomes exposed to the crushing pressure of the car wheels. This crushing pressure results in causing the fiber to fracture and split allowing moisture to enter and thereby quickly impairs the durability of the fiber and its proper functioning as an insulation between the rail ends. Furthermore, the effect of the head of the end post being exposed directly to the pounding of the car wheels is that the blows imparted to the head of the end post are in turn transmitted thereby to the side plates of insulation in that type of joints where such insulation is placed between the undersides of the head of the rails and the joint bars, thereby impairing or injuring said side plates of insulation.

Accordingly, the chief object of the present invention is to provide a modified construction of insulator for the end post insulation of a rail joint, whereby such insulator will be relieved itself from the crushing pressure incident to the pounding of the car wheels, and will also be prevented from transmitting the car wheel blows to the side or head insulation of the joint. Furthermore, it is proposed to provide a

novel formation of insulator or end post so that it will be relieved from undue pressure not only from the car wheels but also from the joint bars.

Another desirable feature and object of the invention is to provide a head formation for the end post which will insure water drainage whereby water will be directed off to the sides of the joint and will not be permitted to settle in the space lying above the end post between the ends of the adjacent rails.

With these and other objects in view which will be appreciated by those familiar with this art the invention consists in the novel construction of insulator or end post herein illustrated, described and claimed.

In carrying forward the invention various structural modifications may be resorted to without departing from the same, but a few preferred and practical embodiments, illustrating the invention, are shown in the accompanying drawings, in which:

Figure 1 is a detail perspective view of the insulating end post for rail joints modified in its design to carry out all of the objects of the present invention.

Fig. 2 is a face elevation of the end post of Fig. 1 shown in its operative relation to the rail section to which it is applied, said rail section appearing in end elevation.

Fig. 3 is a view similar to Fig. 2 showing a modification, embodying the essential features and principles of the invention.

Fig. 4 is a view similar to Figs. 2 and 3 illustrating another modification having the essential features and functions of the invention.

Like references designate corresponding parts in the several figures of the drawings.

The modified end post construction contemplated by the present invention differs primarily from the ordinary end post in the particular of having a less cross-sectional area than the ordinary end post for a given rail section, while at the same time being so shaped as not only to be relieved itself from crushing pressure from the car wheels, but also whereby it will not transmit the car wheel blows to other parts of the insulation in the joint. Various end post formations may be designed to carry out these features and functions and by way of illustration reference is first made to the construction

of end post shown in Figs. 1 and 2 of the drawings. This end post may be made of indurated fiber or any insulating material available and suitable for the purpose and 5 includes the usual relatively narrow web member 1, the head member 2, and the base member 3 formed with the usual laterally extending base flanges 4. Said various members 1, 2, 3 and 4 provide a body 10 responding substantially and approximately to the cross-sectional shape of a rail end. In adapting the improvements of the present invention to an insulator or end post of the form indicated it is proposed, in 15 the construction shown, to have the head member 2 of the end post body of less depth vertically than the head of the rail R to which it is applied. This is accomplished by providing the head member 2 with a reduced 20 top clearance edge 5 formed by cutting away the top edge portion of the insulator body sufficiently so that it will be disposed definitely a sufficient distance below the running surface of the rail so as not to 25 be exposed to the pounding action of the car wheels. In the particular form of the invention shown in Figs. 1 and 2 of the drawings, the cut-away or reduced edge portions 5—5 may be crowned or peaked to 30 provide a centrally located peak 6 with the edges 5 sloping downwardly and outwardly from such peak, thereby making what may be termed a water shed which will effectually drain off water to the sides of the joint 35 and prevent it from standing in the space above the top edge of the end post.

In co-operative relation to the reduced top clearance edge or edges 5 of the end post the head member 2 is further provided at 40 the under sides thereof with the reduced clearance shoulders 7 provided by cutting away the under sides of the head member 2 sufficiently so that the edges or shoulders 7 will be disposed a distance above and away 45 from the under sides of the head of the rail. The effect of this construction is to leave the under sides of the head member 2 of the end post out of contact with and clear of the side plates of insulation 8 which 50 may be employed in the joint, these side plates of insulation being indicated by the dotted lines in Fig. 2 of the drawings. It is by reason of this construction and relation of parts that the end post even though 55 subject to a car wheel blow will not communicate such blow to the side insulation of the joint, thus greatly improving the maintenance conditions in the joint.

In connection with the feature of providing the head member of the end post with reduced clearance shoulders 7, which are adapted to be out of contact with side pieces of insulation 8, it will be observed from Fig. 3 of the drawings that a detail of 60 construction which may be resorted to is

that of providing the bottom corners of the head member 2 of the end post with guard projections or lips 9 which extend to the plane of the undersides of the head of the rail (and therefore have a limited contact with the head fiber of the joint) and thereby exclude and prevent entrance of conductive matter into the spaces provided by the reduced clearance shoulders 7. Substantially the same function of excluding 70 the conductive matter is performed by the structure shown in Fig. 2 of the drawings wherein the reduced clearance shoulders 7 are provided by reentrant angles made in the undersides of the head member of the 80 end post, leaving the bottom corners of said head member of the end post substantially flush with the faces at the undersides of the rail heads. In Fig. 4 of the drawings the plain formation of the head member of the 85 end post is observed both as to the reduced top clearance edge 5 and as to the reduced clearance shoulders 7 at the undersides of the head member of the post, but in all of the forms the head member of the end post 90 has desirable features and functions above explained.

It has already been pointed out that the invention also contemplates a construction of end post wherein the same is relieved from 95 the pressure of the joint bars, and in Fig. 2 of the drawings, that desirable result is accomplished by providing the end post at the inner corners of the upper side of its base member 3 with the reentrant clearance edges 10 which are disposed materially below the inner corner portions of the upper side of the rail flanges so that the splice bars cannot pinch or bind upon the end post edges in 100 these locations. In this form of the invention it is to be noted that the reentrant clearance edges 10 will be useful in that type of joints where the splice bar has an easement above the outer portion of the base flange of the rail. But, in cases where the 110 splice bar has no easement over the upper surface of the base flange of the rail the base member of the end post body will have the upper edges 11 of its flanges (see Fig. 4) of reduced width throughout so that such 115 edges will be disposed entirely below the entire upper surface of the base flanges of the rail, thereby protecting the base member of the end post from binding pressure of the foot of the joint bar, as and for the purposes 120 explained.

From the foregoing it is thought that the construction and many advantages of the herein described improvement in insulating end post for rail joints will be apparent 125 without further description, and it will be understood that changes in the form, proportion and minor details of construction may be resorted to without departing from the spirit or scope of the appended claims or 130

sacrificing any of the advantages of the invention.

We claim:—

1. An insulating end post including a head member provided with reduced clearance edges at the top and undersides thereof.
2. A insulating end post provided with reduced clearance edges at the top and undersides of its head member and at the top 10 of its base member.
3. An insulating end post provided with reduced clearance portions at the undersides of its head member to provide easement from the head fiber of the joint.
4. An insulating end post provided at the underside of its head member with reëntrant edges forming clearances from the head fiber of the joint and leaving the bottom corners of said head member substantially flush 15 with the undersides of the head of the rail to which it is applied.
5. An insulating end post having a peaked top edge forming a water shed.
6. An insulating end post provided with reëntrant clearance portions at the inner corners of the top edges of its base member. 25
7. An insulating end post having a head member provided at its top with a reduced top clearance edge, at the undersides of its head member with reëntrant reduced portions, and at the inner corners of the upper edges of its base member with reëntrant clearance portions. 30

In testimony whereof we hereunto affix our signatures in the presence of two witnesses. 35
